UNITED STATES PATENT OFFICE.

JOSEPH BRANDWOOD, OF WABAN, MASSACHUSETTS.

COLLAPSIBLE HOLDER FOR YARN PACKAGES.

Application filed November 30, 1925. Serial No. 72,307.

In the winding of yarn packages, more particularly in the form of yarn cheeses, which are cross wound and therefore of a soft nature in the compact wound form, a 5 central tube or holder is provided on which the yarn is wound. When it is desired to dye such a cheese in the wound form, by the passing of such fluids through the yarn mass, it has been hitherto necessary to re- 10 move such central tube, and afterwards replace it or insert in the central bore which it occupied a holder of some other stiff material. The weight and cost of the tube or other holder adds considerably to the cost 15 of the yarn in handling and shipment, with the addition of the cost of shipment of the tubes or holders back to the source, when the cheeses have been wound off by the pur- 20 chasing. The percentage of waste of these tubes or holders is also high.

The function of these tubes when re- 25 inserted in cheeses is to prevent the cheese bore from closing with resultant "stabbing" of the inner coils of the windings when the cheese is placed on a spindle for winding off. My present invention has for object a 30 means for keeping the bore of a cheese open to prevent possible damage to the inner yarn windings without the use of stiff tubes or the like, with a minimum of cost, the weight added to each cheese being infinitesimal.

According to the said invention I provide a perfectly flexible tube which may be placed upon a spindle and the cheese wound there- 35 upon, or the tube may be inserted in the cheese bore at any point in the treatment of the said cheese, if the latter has been wound upon a stiff tube or the like, after the removal of the latter. The cheeses may there- 40 fore be packed closely for shipment, some compression of the said cheeses being permissible, and the presence of the flexible holder in the bore of each ensures that at any time each cheese may be placed upon a 45 spindle for winding off or any other treatment without danger of such spindle becoming entangled with the inner yarn windings, thus "stabbing" and spoiling the cheese.

The accompanying drawings sufficiently 50 indicate an embodiment of my invention.

Figure 1 is a cross section of a cheese and

Figure 2 is an end elevation of a cheese in a collapsed condition.

The cheese indicated at 3 may be a cheese 55 which has been wound upon a stiff central tube, the latter having been removed and

the flexible member 4 inserted in its place. The flexible tubular member 4 may be of stockinette or other material which is perfectly flexible and yet will permit of the 60 passage of fluids therethrough if the cheeses are to be subjected to fluid treatment, as indicated for instance in the specification to prior Letters Patent of the United States No. 1,454,312, granted the 8th day of May 1923. 65 Or, with this or some analogous treatment in view, the cheeses may be originally wound upon a spindle as indicated for instance in broken lines at 5 Figure 1 on which the flex- 70ible tubular member 4 has previously been placed.

To facilitate the positioning of the cheese upon a spindle with the member 4 within the bore of the said cheese, the ends of such member, or one end thereof, may project 75 slightly as shown in the drawing. When to be placed in the cheese after the latter has been wound, the tube may simply be flattened and rolled up and thus decreased in bulk, being in that condition inserted in the bore 80 of the cheese, where its natural resiliency will allow it to expand, and remain in position by contact with the inner windings of the cheese yarn.

It will be understood that if the cheeses 85 are not to be subjected to fluid treatment in their compact wound form as cheeses, the porosity of the tube is not a consideration, and the said tube may still be flexible, for the purpose of my invention, whilst being 90 of a stronger and more closely woven and cheap fabric.

Figure 2 shows a cheese in a slightly col- 95 lapsed condition, as it may be in a case in which a plurality of the cheeses have been packed, the tube 4 as will be seen having collapsed also. The insertion of a spindle within the tube 4, or the placing of the cheese upon a spindle which spindle passes within the tube 4, can be effected with perfect safety 100 to the yarn windings.

The flexible tubular member may be man- 105ufactured by any means known in the arts. For instance, they may be woven on a circular loom to the correct diameter and in lengths which are afterwards cut to size, or they may be of sheet fabric cut to length and width, turned over, and stitched to form tubes.

Obviously the invention may if desired be 110 applied to any yarn package which has been wound in the compact form, as here it is

necessary to ensure that the inner windings of the package adjoining a central bore therein, shall not be disarranged by the insertion of a spindle or the like, within the 5 bore.

I claim:—

As a central holder for a yarn cheese, a tube of permeable fabric said tube being of the same diameter throughout and the whole 10 of said tube being collapsible transversely

and longitudinally responsively to any lateral and longitudinal pressure applied to a plurality of cheeses when fitted with the holders to form the said plurality of cheeses into a yarn mass as even and compact of 15 yarn as a single cheese.

In testimony whereof I have hereunto set my hand.

JOSEPH BRANDWOOD.
